UNITED STATES PATENT OFFICE.

HIRAM K. WHITNER, OF NEW YORK, N. Y.

RAILWAY-SWITCH.

SPECIFICATION forming part of Letters Patent No. 394,744, dated December 18, 1888.

Application filed June 16, 1888. Serial No. 277,322. (No model.)

To all whom it may concern:

Be it known that I, HIRAM K. WHITNER, of New York, in the county and State of New York, have invented a certain new and useful 5 Improvement in Railway-Switches, of which the following is a specification.

I will describe a railway-switch embodying my improvement in detail, and then point out the novel features in claim.

10 In the accompanying drawings, Figure 1 is a plan or top view of a railway-switch embodying my improvement. Fig. 2 is a transverse section thereof, taken on the plane of the line *x x*, Fig. 1.

15 Similar letters of reference designate corresponding parts in both the figures.

A A' designate the switch-points. These switch-points may be of the usual construction to operate in conjunction with rails B B'. The switch-points are connected together by a switch-rod, C. In the example of my improvement shown the switch-rod is operated by a motion-plate, D. In this motion-plate an approximately ogee-shaped slot, *d*, is employed, extending in the direction of the 25 length of the plate. Into this slot extends a pin or projection, *a*, from the switch-rod C.

E designates a rod connected to the motion-plate D and extending to switch-operating 30 mechanism, (not shown in the drawings,) by which longitudinal motion is imparted to the motion-plate D. It will be readily seen that as the motion-plate is moved longitudinally the pin *a* is caused to follow the slot *b*, 35 whereby the switch-rod C is caused to move in a direction at right angles to the track, and the switch-points will be shifted from one side to the other, according to the direction in which the motion-plate is moved.

40 Heretofore motion-plates employed in the operation of switch-points have been provided with slots comprising two straight portions extending in the direction of the length of the motion-plate and another straight portion 45 extending between the two just mentioned, but at an angle, whereby sharp angles were formed at the junctions of the several portions of the slot. Great difficulty has been experienced in causing the movement of the 50 motion-plate, and consequently of the switch-points, at that point in the motion of the motion-plate wherein the pin or projection on

the switch-rod turns these angles, this being the initial movement imparted to the switch-points. For the purpose of overcoming this 55 difficulty and occasioning an even and easy movement of the switch-points, I make the slot in the motion-plate approximately ogee-shaped—that is to say, the junctions of the several portions of the slots are made curved 60 or rounding, as shown. I also employ rollers *d*. These rollers are journaled in brackets F, which brackets are secured to a railroad-tie in such position that when the switch has been moved into one of its extreme positions, 65 1 of the switch-points—as, for instance, the switch-point A'—will rest upon the top of its adjacent roller *d*, while the switch-point A will be between its adjacent roller *d* and its adjacent portion of the track B'. When in 70 this position, it will be seen that the roller *d* adjacent to the switch-point A will operate to largely prevent accidental displacement of the switch-points. In this position also, as before stated, the switch-point A' is resting 75 upon the top of its adjacent roller *d*. If, now, it is desired to shift the switch-points into their other extreme position—as, for instance, the position the opposite of that shown—the switch-point A' will of course be moved to 80 toward the rail B, and the switch-point A will ride up onto the roller *d* adjacent to it. This motion will have been accomplished before the motion-plate D shall have been moved far enough in one direction to cause the switch- 85 points to reach a point about midway in their side-to-side movement. After passing that point, the switch-points A A' will have passed the center of their movement and of the rollers *d*, and will consequently be assisted in 90 their movement toward the rail B by their descent upon the curved surfaces of the rollers *d*. This assistance which the rollers offer to the movement of the switch-points in either direction is sufficient to enable the motion- 95 plate D to be moved easily far enough in either direction to carry the pin *a* out of the curved or angularly-extending portion of the slot.

It will also be seen that by my improvement when the switch-points are being shifted from one position to another, and are riding upon the rollers, that they are elevated above the ties of the track, and consequently the 100

resistance offered by friction between the ties and the switch-points is overcome. Therefore very much less power is required to shift the switch-points than where the switch-points 5 are allowed to rest upon the ties.

I do not wish it to be understood that I limit myself to the use of the rollers for assisting the movement of the switch-points with the peculiar mechanism for operating the switch-points which I have illustrated, as the same is equally applicable to other devices for moving the switch-points where the strain experienced is greatest when the switch-points are at or near midway in their side-to-side 15 traverse.

By my improvement I am enabled to use the motion-plate for operating the switch-points—such, for instance, as I have illustrated, having a much sharper curve or angle 20 than can be employed in the usual form of such motion-plates. This is advantageous, because it shortens the length of the motion-plate, and thereby occasions a much more rapid shifting of the switch-points.

In my description I have more particularly 25 described the movement of the switch-points from the rail B' to the rail B; but of course it is to be understood that the operation is the same in whichever direction the switch-points are moved.

What I claim as my invention, and desire 30 to secure by Letters Patent, is—

In a railway-switch, the combination, with switch-operating mechanism, of switch-points and rollers with which the switch-points will 35 contact and over which they will pass when being shifted from side to side, said rollers being arranged in such position that when the switch-points occupy either of their extreme positions one of the switch-points will 40 rest upon one of said rollers and the other of said switch-points will be between another of said rollers and its adjacent rail, substantially as specified.

H. K. WHITNER.
